[57] CLAIM

The ornamental design for a handle assembly for a physical exerciser, as shown and described.

DESCRIPTION

FIG. 1 is a perspective view of a handle assembly for a physical exerciser showing my new design;

FIG. 2 is a left side elevational view, the right side view being a mirror image thereof;

FIG. 3 is a bottom plan view;

FIG. 4 is a top plan view;

FIG. 5 is a rear elevational view thereof; and,

FIG. 6 is a front elevational view thereof.
